ORDNANCE

John C. Trotter, Williamsville, and John L. Jewett, Buffalo, N. Y., assignors to Bell Aircraft Corporation, Buffalo, N. Y.

Application March 13, 1942, Serial No. 434,528

14 Claims. (Cl. 89—37.5)

This invention relates to ordnance, and more particularly to mounts and ammunition feed mechanisms for use in conjunction with automatic firearms of the machine gun type, or the like.

One of the objects of the invention is to provide an improved mounting arrangement for machine guns or automatic cannon in conjunction with military vehicles such as tanks, airplanes, or the like. Another object of the invention is to provide an apparatus of the character described wherein there is incorporated in improved manner an ammunition feeding means accessory to the usual ammunition feed mechanism of the gun. Another object of the invention is to provide an apparatus for the purpose described wherein provision is made for aiming adjustments of the mounted gun in improved manner. Other objects and advantages of the invention will appear from the specification hereinafter.

In the drawings:

Fig. 1 is a fragmentary side elevation of a gun mount and an ammunition feed assist mechanism of the invention installed within the gunner's cockpit of a tank or airplane, or the like;

Fig. 2 is an enlarged fragmentary view of the ammunition feed assist portion of the mechanism;

Fig. 3 is a rear view of the mechanism of Fig. 2;

Fig. 4 is a rear view of the mechanism of Fig. 1; and

Fig. 5 is a top plan thereof with the machine gun removed.

The invention is illustrated in the drawings in connection with a machine gun which is indicated generally at 10 as being mounted within an enclosure 12 comprising a gunner's cockpit canopy of an airplane, or a tank, or the like. The gun 10 is illustrated as being fitted with a telescopic sight 14, and is carried by a pair of parallel bearer tubes 15—15 at opposite sides thereof so as to be reciprocable relative to the bearer tubes in response to recoil and counter-recoil forces of the gun firing operation. The bearer tubes each carry rigidly extending bracket arms 16—16 for pivotally engaging through means of trunnions 17—17 the upper end portions 18—18 of a fork or gun mount yoke. Thus, the gun and bearer tube unit is freely pivotable about a horizontal axis extending through the aligned trunnion bearings 17—17 for elevational adjustments of the gun aim.

The gun mount yoke 18 is mounted at its lower end so as to be freely pivotable within a socket portion 19 of a bracket 20. The bracket 20 is connected intermediately of its ends by means of a pivot pin 22 to the upper end of a gun mount column designated generally by the

5 numeral 24. A screw connection device 26 is provided on the column 24 so as to register with the lower end of the bracket 20 whenever the latter is in operative position against the column, as illustrated by solid lines in Figs. 1 and 2. Thus, it will be understood that the bracket 20 is arranged to be normally held rigidly against the column 24 by means of connection devices 22—26 in such manner that the yoke arms 18—18 extend substantially vertically above the upper end of the column 24 to support the gun 10 at the upper end of the column while being freely rotatable relative thereto about the horizontal trunnion axis of the bearings 17—17 for elevational aiming adjustments of the gun. Also, since the gun support yoke is free to rotate within the socket 19 of the bracket 20 the gun may be readily shifted for azimuth adjustments of the gun aim relative to the mounting column 24.

10 However, whenever the gun battery is inactive, the screw connector 26 may be manually released so that the bracket 20 is free to pivot in clockwise direction (Figs. 1 and 2) as to the 15 broken line position thereof in Fig. 2, whereby the gun 10 may be stowed below the deck portion 28 of the gun battery enclosure, as indicated by the broken line position of the gun barrel at 29 (Fig. 1). Thus, the gun will at all 20 times be readily available for quick withdrawal from stowed position into upright firing attitude, whereupon the bracket 20 will register with the connection device 26 for manual locking of the gun yoke bracket relative to the mounting column 24 in gun operative position.

25 The gun mount column 24 is of modified Z shape in side elevation; that is, it comprises a vertically disposed upper end portion 30; a horizontally disposed intermediate portion 32; and a vertically disposed lower end portion 34, 30 formed to provide an integral gun support column having axially offset and vertically extending upper and lower end portions. The lower end portion 34 is supported upon stationary 35 structure of the gun battery housing by means of vertically spaced bearings 36—38. Thus, the gun mount column is normally free to rotate about a vertical axis extending through the bearings 36—38 whereupon the upper end portion 30 of the column will be thereby caused to sweep 40 in an arc about said axis.

45 A forked bracket 40 is pivoted at 42 by means of a transverse pin to the lower end portion 34 of the gun mount column, and is arranged to extend rearwardly therefrom to support a gunner's seat 44 at such position that the gunner 50 may be comfortably seated thereon while straddling the gun mount column so as to be positioned within most convenient access to the gun control handles and sighting device. A crank

arm 46 is provided to extend rigidly from the bracket 40 beyond the pivot device 42 for connection to one end of a cable leading into connection with an elastic cord 48. The cord 48 is fixed at its opposite end to any suitable stationary structure, and it will be understood that the crank and elastic cord mechanism will be arranged so as to be adapted to substantially balance the weight of the gunner and the gunner's seat. Hence, the gunner may with utmost facility regulate his vertical disposition relative to the gun mount column by application of suitable pushing forces through his feet and against the cockpit floor and through his hands against the rear end of the gun. A sloping floorboard 49 is preferably provided as shown for this purpose.

Thus, it will be understood that as the gunner sits upon the seat 44 his legs straddle the lower end portion of the gun mount column 24 and his feet may be firmly planted in relatively widely spaced relation against the floorboard 49. Consequently, the gunner and the gun are so mounted as to be substantially diametrically opposed in relation to the axis of rotation of the gun mount column; and through application of simple pressure forces by alternate legs against the floor board the gunner may with utmost facility cause the entire gun mount mechanism to be adjusted in azimuth for gun aiming purposes. As explained hereinabove, however, the gun 10 is mounted relative to the gun mount column 24 so as to be additionally adjustable in azimuth relative to the upper end portion of the gun mount column irrespective of the condition of angular adjustment of the gun mount column relative to its axis of rotation. Thus, the gun 10 is mounted to be aimed with utmost facility through azimuth adjustments provided primarily through rotation of the gun mount column 24 about the vertical axis of the lower portion thereof in response to pressure force differentials transmitted through the legs of the gunner against the floorboard 29. In addition and at all times, secondary azimuth adjustments of the gun in connection with aiming thereof are obtainable through simple rotation of the gun about the vertical axis of the socket portion 19 of the gun support bracket 20, as may be caused by application of deflecting forces against the rear end of the gun through the hands of the gunner; while elevational adjustments thereof about the axis of the trunnions 17-17 are effected through corresponding upwardly and downwardly directed pressure forces applied through the gunner's hands to the rear end of the gun, while the gunner's seat raises or lowers accordingly.

A plate 50 is mounted to extend rigidly from stationary structure of the gun battery enclosure and so as to be disposed adjacent to the laterally offset portion 32 of the gun mount column and parallel to the plane of oscillation thereof. A latching mechanism 52 is provided upon the gun mount column for detachably latching the latter in different positions relative to the plate 50. For example, the latching mechanism 52 may conveniently comprise an electric solenoid actuated mechanism having a latch finger 54 adapted to project into recessed portions of the plate 50 which are arranged in an arc concentrically of the axis of rotation of the gun mount column 24. The solenoid mechanism 52 may be conveniently controlled by a manually operable switch mounted upon the hand grip devices at the butt end

of the gun 10. However, it will be understood that any other suitable form of latching and control mechanisms may be employed for the purpose.

An arcuate rail 56 is mounted to extend from a stationary portion of the gun battery enclosure to parallel the orbit of oscillation of the upper end of the gun mount column 30, and a second latch device 58 is mounted upon the gun mount column for controllably locking the latter into engagement with suitably apertured portions of the rail 56, as indicated at 59. As in the case of the latch mechanism 52, the latch device 58 may be conveniently provided to comprise a solenoid actuated mechanism adapted to be controlled by the same manually operable switch mounted upon the gun hand grip devices. Thus, the latch devices 52-58 may be arranged to be operated simultaneously and in response to actuation of a single control device which is located within convenient reach of the gunner's hands while gun aiming and firing operations are in progress; and whenever the gunner has accomplished proper primary adjustment of the gun mount position in azimuth through rotation of the entire gun mount and gunner's seat assembly about the axis of the column portion 34, he may thereupon actuate the latch control device to cause the gun mount column to be locked in its adjusted position relative to the plate 50 and to the rail 56.

Consequently, the gun mount column will be supported at any such position of azimuth adjustment in an improved manner from the standpoint of effective resistance to horizontally directed reaction forces imposed upon the gun mount structure incidental to firing of the gun. This is because the lower end portion of the gun mount column is at all times firmly supported against horizontal deflection by means of the substantially spaced bearings 36-38. The intermediate portion of the gun mount column is firmly supported at opposite ends thereof by means of its connection to the lower column end portion 34 and to the plate 50 through means of the latch mechanism 52; and finally, the upper end portion of the column 30 is firmly fixed by means of the widely spaced latch devices 52-58 to stationary structure of the gun mount enclosure. Particular attention is directed to the fact that because the latch device 58 comprises a pin member 59 slidable vertically into engagement with the rail 56, the extreme upper end portion of the gun mount column is thereby fixed to stationary supporting structure for improved resistance to gun firing reaction forces in all horizontal directions. Therefore, it will be understood that the gun mount device of the invention provides an arrangement whereby a gun of relatively heavy caliber may be satisfactorily mounted upon an upper laterally offset end of a substantially elongated gun support column which is pivotally mounted at its lower end for rotation about a vertical axis, whereby increased facility for gun aiming purposes and improved rigidity for firm support of the gun is provided.

Ammunition for the gun 10 is arranged to be fed thereto in the form of a continuous belt of cartridges from a container which is disposed at a position remote from the gun mount arrangement as indicated at 60. The cartridge belt is indicated at 62 as being trained around suitable rollers so as to issue freely from the magazine 60 and to train toward the base of

the gun mount column 24. To this end the cartridge belt 62 may be conveniently arranged to pass below the floor line of the gunner's compartment as indicated at 64 (Fig. 1) and thence around a roller 65 fixed to the stationary floor structure so as to train upwardly therefrom through the interior of the gun mount column portion 34. Rollers 66-68 within the column 24 at the bends thereof further guide the cartridge belt so as to issue freely through the upper end of the gun support column just below the position of the gun ammunition feedway and approximate vertical alignment therewith. It will be understood that the cartridge belt will be easily capable of twisting between the positions 15 of the rollers 65-66 in connection with azimuth adjustments of the gun mount column 24 about the axis of its lower portion.

An ammunition belt feeding mechanism is housed in a casing 70 mounted upon the upper end of the column 24. A sprocket wheel 72 having teeth shaped to engage in geared relation with the cartridge belt 62 is rotatably mounted within the casing 70. A gear train 74 engages the sprocket 72 and is arranged to be driven by an electric motor 75 which is coupled thereto. The motor-sprocket unit is set within the housing 70 at one end thereof, and a free roller 76 is mounted in line with the interior opening of the column 24 for guiding the change of direction of cartridge belt movement therefrom so as to feed freely into engagement with the sprocket 72. From the sprocket 72 the cartridge belt is arranged to train toward the opposite end of the housing 70 and to be looped thereat about a free roller 78 and thence to train in return direction to pass around a guide roller 79 for feeding from the casing 70 in the direction of the ammunition feedway of the gun 10. Thus, it will be understood the ammunition belt is looped within the housing 70 in such form as to comprise a lower strand 80 and an upper strand 82.

The roller 78 is carried by bearings 84-84 extending at opposite ends thereof into sliding engagement with opposed slotted portions 86-86 at opposite walls of the housing 70. Thus, the roller 78 is mounted to be movable longitudinally of the housing structure in connection with shortening and lengthening of the looped portion 80-82 of the cartridge belt. A compression spring 88 is mounted within the casing to resiliently urge the roller 78 to move relative to the housing 70 toward its extreme right hand end position as illustrated in Fig. 3 and thus to maintain the looped portion 80-82 of the cartridge belt in maximum extended condition. However, it will be appreciated that whenever the machine gun feed pawl mechanism drags upon the cartridge belt to commence feeding of ammunition in connection with a gun firing operation the upper strand portion 82 of the cartridge belt will be thereby tensioned against the weight of the cartridge belt therebelow to cause the roller 78 to be pulled toward the left as viewed in Fig. 3 against the action of the spring 88. A control finger 90 is carried by the shaft of the pulley 78 to move therewith in response to the pull of the cartridge belt referred to hereinabove, and to thereupon bear against the actuating member of a switch 92 controlling the power supply circuit of the motor 75. The switch 92 is so arranged that whenever the actuating member thereof is deflected to the left as viewed in Fig. 3 the power supply circuit of the motor 75 will be closed to energize the motor for driving the sprocket 72 in

such direction as to propel the cartridge belt 62 in the direction of gun feeding.

The motor 75 will of course be provided of such power and speed characteristics that when energized it will propel the cartridge belt either at a speed equal to the ammunition feed requirements of the gun or slightly in excess thereof, whereby the ammunition feed pawl mechanism integral with the gun 10 will be substantially relieved of the loads incidental to overcoming inertia of the cartridge belt upon commencement of each gun firing operation and to elevate the cartridge belt 62 to the level of the gun. Upon cessation of each gun firing operation, or upon overtaking of the gun feed pawl mechanism by the cartridge belt driving operation of the sprocket 72, the looped portion 80-82 of the cartridge belt will be thereby relaxed to enable the spring 88 to force the switch control roller 78 to retreat to switch-inoperative position as illustrated in Fig. 3, whereupon the power supply circuit of the motor 75 will be interrupted and driving propulsion of the cartridge belt by the feed assist mechanism will cease.

Preferably, a cartridge belt twist relief device will be employed as indicated generally at 95 between the positions of the discharge roller 79 of the feed assist device and the position of the ammunition feedway portion of the gun 10. For example, a device for this purpose is illustrated as comprising a funnel-like bracket 96 mounted to extend rigidly from the ammunition feedway portion of the gun. An annular feed throat 97 is carried upon the bracket so as to be freely rotatable about a horizontal axis projecting laterally and centrally of the ammunition feedway portion of the gun, as by means of rollers 98 carried by the bracket 96 and disposed to engage a grooved circular track portion 99 of the throat 97 at radially spaced intervals. A cartridge belt guide roller 100 is carried by the throat 97 to rotate freely relative thereto and to engage the cartridge belt 62 in trained relation thereabout for guiding the cartridge belt through the throat and funnel devices 97-96 into gun feeding position. A housing 101 is formed to encompass the roller 100 to facilitate guiding of the cartridge belt about the roller and into the ammunition feedway of the gun.

50 Thus, it will be understood that, as viewed in Fig. 2, the cartridge belt 62 will issue from the feed assist mechanism and will then twist toward the direction of the cartridge belt guide device 95, while the pull of the cartridge belt upon the roller 45 carrying throat 97 of the guide device will cause the latter to rotate upon the rollers 98 to assume an attitude whereby the roller 100 will substantially bisect the angle between the direction of movement of the cartridge belt toward and away from the guide device. Consequently, excess twisting or "kinking" of the ammunition belt at the cartridge feedway slot of the gun is avoided; and it will be understood that as the gun is pivoted about the axis of the trunnions 16-16 in connection with elevational aiming adjustments thereof the rotating roller portion of the guide device 95 will shift automatically relative to its mounting bracket so as to avoid acute twisting of the cartridge belt between the positions of the guide device and the ammunition feedway 65 of the gun to prevent jamming of the cartridge belt in the feedway slot of the gun under all combat conditions.

Although only one form of the invention has 70 been shown and described in detail, it will be

apparent to those skilled in the art that the invention is not so limited but that various changes may be made therein without departing from the spirit of the invention or the scope of the appended claims.

We claim:

1. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway therethrough for feeding of a belt of ammunition therethrough for feeding the gun mounted upon said mounting means, an ammunition belt drive device mounted upon the ammunition discharge end portion of said gun mount column and operable for propelling said ammunition belt so as to substantially relieve the gun feed pawl mechanism of the loads incidental to elevating said ammunition to the level of the gun and accelerating the movement of said ammunition incidental to commencement of each gun firing operation, and latch means carried by said gun mount column for engagement with stationary structure adjacent the orbit of movement thereof incidental to rotation of said gun mount column about said vertical axis.

2. A gun mount comprising an extended tubular column having an ammunition intake end portion rotatably mounted upon a base support to pivot about an axis and a laterally projecting portion extending therefrom and terminating in an ammunition discharge portion, means carried by the outer end of said projecting portion of said column for mounting a gun thereon at a position eccentrically of said axis and adjacent the point of ammunition discharge, said gun mount column being hollowed to provide a closed passageway for feeding of a belt of ammunition therethrough for feeding the gun mounted upon said mounting means, an ammunition belt drive device mounted upon the ammunition discharge end portion of said gun mount column and operable for propelling said ammunition belt and to overcome the loads incidental to elevating said ammunition to the level of the gun and accelerating the movement of said ammunition incidental to commencement of each gun firing operation, and latch means carried by the outer end of said gun mount column for detachable engagement with stationary structure adjacent the orbit of movement thereof incidental to rotation of said gun mount column about said vertical axis subsequent to adjustments of said column about said axis.

3. A gun mount comprising a vertically extended tubular column having a lower end ammunition intake portion rotatably mounted upon a base support to pivot about a vertical axis and an intermediate laterally projecting portion extending therefrom and carrying an upwardly bent end portion terminating in an ammunition discharge portion, means carried by the upper end portion of said column for mounting in universally pivotable relation thereon a gun at a position eccentrically of said vertical axis and adj-

cent the point of ammunition discharge, said gun mount column being hollow to provide a closed passageway for feeding of a belt of ammunition therethrough for feeding the gun mounted upon said mounting means, and latch means carried by said gun mount column both at the lower and upper end portions of the upwardly bent end portions of said column for engagement at separate points with corresponding stationary structures adjacent the orbit of movement thereof incidental to rotation of said gun mount column about said vertical axis for azimuth adjustments of said gun mount.

4. In combination, a gun enclosure having an upper deck and a gun emplacement opening therein, a gun mount comprising a vertically extended tubular column having a lower end ammunition intake portion rotatably mounted upon a base support to pivot about a vertical axis and an upper laterally projecting portion extending therefrom and terminating in an ammunition discharge portion disposed adjacent said gun emplacement opening, swivel yoke means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway therethrough for feeding of a belt of ammunition therethrough for feeding the gun mounted upon said mounting means, and latch means carried by said gun mount column projecting portion for engagement with stationary structure adjacent the orbit of movement thereof incidental to rotation of said gun mount column about said vertical axis, said swivel yoke means being bodily adjustable relative to said gun mount column under non-combat conditions for pivoting said yoke to stow said gun below the deck of said enclosure.

5. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway for a belt of ammunition feeding therethrough to the gun mounted upon said mounting means, an ammunition belt drive device mounted upon the ammunition discharge end portion of said gun mount column and operable for propelling said ammunition belt toward said gun, latch means carried by said gun mount column projecting portion for engagement with stationary structure adjacent the orbit of movement thereof incidental to rotation of said gun mount column about said vertical axis, and a gunner's seat mounted upon said column to extend diametrically opposed relative to said laterally projecting column portion.

6. A gun mount comprising a vertically extended tubular column having a lower end ammunition intake portion rotatably mounted upon a base support to pivot about a vertical axis and an upper laterally projecting portion extending therefrom and terminating in an ammunition

discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway for a belt of ammunition feeding therethrough to the gun mounted upon said mounting means, an ammunition belt drive device mounted upon the ammunition discharge end portion of said gun mount column and operable for propelling said ammunition belt toward said gun, latch means carried by said gun mount column projecting portion for engagement with stationary structure adjacent the orbit of movement thereof incidental to rotation of said gun mount column about said vertical axis, said swivel yoke means being bodily adjustable relative to said gun mount column under non-combat conditions for pivoting said yoke to stow said gun below the deck of said enclosure, and a gunner's seat mounted upon said column to extend diametrically opposed relative to said laterally projecting column portion, and counterbalance means coupled to said seat and extending into said hollow column for counterbalancing the weight of the gunner and said seat.

7. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway for a belt of ammunition feeding therethrough to the gun mounted upon said mounting means, an ammunition belt drive device mounted upon the ammunition discharge end portion of said gun mount column and operable for propelling said ammunition belt toward said gun, latch means carried by said gun mount column projecting portion for engagement with stationary structure adjacent the orbit of movement thereof incidental to rotation of said gun mount column about said vertical axis, and a gunner's seat mounted upon said column to extend diametrically opposed relative to said laterally projecting column portion, and reel means mounted adjacent said gun for training of said cartridge belt therearound between the positions of said belt drive device and the feedway port of said gun for preventing acute twisting of the cartridge belt in the feedway port of said gun.

8. In combination, a gun enclosure having an upper deck and a gun emplacement opening therein, a gun mount comprising a vertically extended tubular column having a lower end ammunition intake portion rotatably mounted upon a base support to pivot about a vertical axis and an upper laterally projecting portion extending therefrom and terminating in an ammunition discharge portion disposed adjacent said gun emplacement opening, swivel yoke means carried by the upper end portion of said column for mounting in universally pivotable relation thereon a gun at a position eccentrically of said vertical axis and adjacent the point of ammunition discharge, said gun mount column portions being hollowed and intercommunicat-

ing interiorly to provide a closed passageway therethrough for feeding of a belt of ammunition therethrough for feeding the gun mounted upon said mounting means, and latch means carried by said gun mount column projecting portion for engagement with stationary structure adjacent the orbit of movement thereof incidental to rotation of said gun mount column about said vertical axis, said swivel yoke means being bodily adjustable relative to said gun mount column under non-combat conditions for pivoting said yoke to stow said gun below the deck of said enclosure, and a gunner's seat mounted upon said column to extend diametrically opposed relative to said laterally projecting column portion.

9. A gun mount comprising a vertically extended tubular column having a vertically disposed lower end portion rotatably mounted upon a base support, said column including an intermediate laterally projecting portion extending from the upper end of said lower end column portion, and a second vertically extending upper end portion carried by the outer end of said laterally projecting column portion, means carried by the upper end portion of said column for mounting a gun thereon so as to be universally pivotable relative thereto, said gun mount column portions being hollowed and intercommunicating interiorly to provide enclosed passageway for belts of ammunition to pass therethrough for feeding the gun mounted upon said mounting means, and an ammunition belt feed assist device mounted upon the upper end portion of said gun mount column and automatically operable in conjunction with the firing operation of a gun mounted thereon for propelling said ammunition belt so as to substantially relieve the gun feed pawl mechanism of the loads incidental to elevating said ammunition to the level of the gun and accelerating the movement of said ammunition incidental to commencement of each gun firing operation, and latch means carried by the upper and lower ends of said second vertically extending column portion of said gun mount column for engagement with stationary structure adjacent the orbit of movement of said latch means incidental to rotation of said gun mount column about the axis of its rotatably supported lower end portion.

10. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway for a belt of ammunition feeding therethrough to the gun mounted upon said mounting means, an ammunition belt drive device mounted upon the ammunition discharge end portion of said gun mount column and operable for propelling said ammunition belt toward said gun, latch means carried by said gun mount column projecting portion for engagement with stationary structure adjacent the orbit of movement thereof incidental to rotation of said gun mount column about said vertical axis, manually operable control means for said latch means carried by said gun adjacent the trigger control portion

thereof, and a gunner's seat mounted upon said column to extend diametrically opposed relative to said laterally projecting column portion.

11. A gun mount comprising a vertically extended tubular column having a vertically disposed lower end portion rotatably mounted upon a base support, said column including an intermediate laterally projecting portion extending from the upper end of said lower end column portion, and a second vertically extending upper end portion carried by the outer end of said laterally projecting column portion, means carried by the upper end portion of said column for mounting a gun thereon so as to be universally pivotable relative thereto, said gun mount column portions being hollowed and intercommunicating interiorly to provide enclosed passageway for belts of ammunition to pass therethrough for feeding the gun mounted upon said mounting means, and an ammunition belt feed assist device mounted upon the upper end portion of said gun mount column and automatically operable in conjunction with the firing operation of a gun mounted thereon for propelling said ammunition belt so as to substantially relieve the gun feed pawl mechanism of the loads incidental to elevating said ammunition to the level of the gun and accelerating the movement of said ammunition incidental to commencement of each gun firing operation, and latch means carried by the upper and lower ends of said second vertically extending column portion of said gun mount column for engagement with stationary structure adjacent the orbit of movement of said latch means incidental to rotation of said gun mount column about the axis of its rotatably supported lower end portion, said latch means being adapted to be controlled by manually operable means carried by said gun adjacent the trigger control portion thereof.

12. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon a gun at a position eccentrically of said vertical axis and adjacent the point of ammunition discharge, said gun mount column portions being hollowed and intercommunicating interiorly to provide a closed passageway for a belt of ammunition feeding therethrough to the gun mounted upon said mounting means, an ammunition belt drive device mounted upon the ammunition discharge end portion of said gun mount column and operable for propelling said ammunition belt toward said gun and comprising a free roller device around which said cartridge belt is looped and means responsive to lateral displacement of said roller device in conjunction with the operation of an elastic control member in response to slackening or tautening forces in said cartridge belt looped portion to make said belt drive device inoperative or operative, latch means carried by said gun mount column projecting portion for engagement with stationary structure adjacent the orbit of movement thereof incidental to rotation of said gun mount column about said vertical axis, and a gunner's seat mounted upon said column to extend diametrically opposed relative to said laterally projecting column portion.

13. A gun mount comprising a vertically extended tubular column having a lower end ammunition intake portion rotatably mounted upon a base support to pivot about a vertical axis and an upper laterally projecting portion extending therefrom and terminating in an ammunition discharge portion, means carried by the upper end portion of said column for mounting in universally pivotable relation thereon, a gun at a position eccentrically of said vertical axis and adjacent the point of ammunition discharge, said gun mount column portions being hollowed and intercommunicating interiorly to provide a closed passageway therethrough for feeding of a belt of ammunition therethrough for feeding the gun mounted upon said mounting means, latch means carried by said gun mount column for engagement with stationary structure adjacent the orbit of movement thereof incidental to rotation of said gun mount column about said vertical axis, and an ammunition belt drive device mounted upon the ammunition discharge end portion of said gun mount column and operable for propelling said ammunition belt so as to substantially relieve the gun feed pawl mechanism of the loads incidental to elevating said ammunition to the level of the gun and accelerating the movement of said ammunition incidental to commencement of each gun firing operation, said belt drive device comprising an electric motor coupled to a belt engaging sprocket and a free roller engaging a reversely turned loop portion of said belt, an elastic force member normally biasing said free roller toward belt full looped condition, and motor control switch means adapted to be actuated to energize said motor upon pulling of said roller against said elastic means to shorten said belt looped portion.

14. A gun mount comprising a vertically extended tubular column having a vertically disposed lower end portion rotatably mounted upon a base support, said column including an intermediate laterally projecting portion extending from the upper end of said lower end column portion, and a second vertically extending upper end portion carried by the outer end of said laterally projecting column portion, means carried by the upper end portion of said column for mounting a gun thereon so as to be universally pivotable relative thereto, said gun mount column portions being hollowed and intercommunicating interiorly to provide enclosed passageway for belts of ammunition to pass therethrough for feeding the gun mounted upon said mounting means, and an ammunition belt feed assist device mounted upon the upper end portion of said gun mount column and automatically operable in conjunction with the firing operation of a gun mounted thereon for propelling said ammunition belt so as to substantially relieve the gun feed pawl mechanism of the loads incidental to elevating said ammunition to the level of the gun and accelerating the movement of said ammunition incidental to commencement of each gun firing operation, and latch means carried by the laterally projecting portions of said gun mount column for engagement with stationary structure adjacent the orbit of movement of said latch means incidental to rotation of said gun mount column about the axis of its rotatably supported lower end portion.
